UNITED STATES PATENT OFFICE.

JOHN P. DE L'EAU, OF LOS ANGELES, CALIFORNIA.

KEY CASE.

Application filed April 16, 1925. Serial No. 23,714.

My invention relates to key cases, suitable for carrying in the pocket, adapted to retain a plurality of keys in convenient arrangement for ready and convenient use.

5 The principal desiderata in devices of this character are that the case occupy a minimum of space, especially in thickness, so it will lie flat in the pocket; that each key be individually retained, to obviate bunching 10 and facilitate selection for use; and that the attaching means for the keys permit their lying flat in the case yet have individual freedom of movement, relative thereto, necessary for convenient use. All of these are 15 satisfied with my device as they are and have been by similar devices heretofore on the market. But in addition to these considerations the object of my invention is to overcome certain objectionable features common 20 to all these prior devices which I have known, to the end that each individual key is more readily accessible and has more freedom of movement relative to the case, and consequently is more satisfactory in use.

25 The principal desiderata in devices of this invention and similar devices heretofore known in the art is that the keys are not only normally retained in the case, in secure and compact arrangement, but they may be individually withdrawn therefrom to an extent which will permit free rotation in a lock, independent of and without interference from the case. This permits a key to be held in one hand and used, as if not attached, while 30 the case is held in the other, or both may be held in one hand.

Another feature of my invention is, that after use the key is automatically drawn into the case to its normal position.

40 These and other features of my invention are more fully set forth in the following specification, reference being made to the accompanying drawings, wherein I have illustrated my preferred specific embodiment.

45 In these drawings,

Fig. 1 is a sectional view taken as indicated by the line 1—1 of Fig. 2;

Fig. 2 is a sectional view, taken as indicated by the line 2—2 of Fig. 1;

50 Fig. 3 is an enlarged fragmentary sectional view, taken as indicated by the line 3—3 of Fig. 1;

Fig. 4 is an enlarged fragmentary sectional view, taken as indicated by the line 55 4—4 of Fig. 1;

Fig. 5 is an enlarged fragmentary sectional view, taken as indicated by the line 5—5 of Fig. 1;

Fig. 6 is an enlarged fragmentary sectional view, taken as indicated by the line 60 6—6 of Fig. 2; and

Fig. 7 is a view similar to Fig. 1 showing the modified form of the device.

Referring now to the drawings the numeral 10 designates a case, which, for convenience of description, I will hereafter term a housing. This may and preferably will be formed of a suitable thin sheet metal; and may, for convenience of manufacture, be made in two parts 11 and 12; the portion 70 11 constituting its body portion while the part 12 constitutes a flat plate cover therefor. These may be secured together by any suitable means, such as rivets 13. This housing 10 may be made in any convenient size and 75 configuration, but preferably it will be comparatively narrow, so as to occupy a minimum of space when in the pocket.

A reel 14 is mounted within the housing 10 upon a transversely disposed pin or stud 80 15. Preferably the stud 15 will be rigidly secured to the back 16 of the portion 11 and the reel rotatable thereon. This reel is formed with a circular recess 17 therein, closed by a plate 18 seating upon an annular 85 shoulder 19. While it is free to rotate upon the stud 15 in the direction indicated by the arrow in Fig. 1, it is normally restrained by the action of a coil spring 20, secured to it at one end, as at 21, and to the stud 15 and 90 at its opposite end. It is also normally held against rotation, by the action of spring 20, in a direction opposite to that indicated by the arrow in Fig. 1, by teeth 22, fixed upon the cover plate 12 concentric with the stud 95 15, normally engaged by similar teeth 23 upon the end plate 24 of reel 14. As shown in Fig. 4, these teeth are formed to permit rotation of the reel 14 in the direction indicated by the arrow in Fig. 1, and hold it 100 against rotation in the opposite direction.

Reel 14 is normally held spaced from the back plate 16 of the housing portion 11, and teeth 22 and 23 normally held in co-active engagement, by the action of a leaf spring 25 interposed between the reel closure plate 18 and the housing back 16. Spring 25 is retained in place by the stud extending through an aperture 26 therein.

In order that the reel 14 may be rotated 110

by the action of spring 20 it is axially movable upon stud 15—against the action of spring 25—to disengage the teeth 22 and 23, by means of a push button 27. This is clearly shown in Fig. 3. It extends through an aperture 29 in the cover plate 12 and is retained in place by an annular flange 30 confined between the plate 12 and the adjacent end plate 24 of reel 14. By pushing 10 inwardly upon the button the reel will be moved axially—against the action of spring 25—disengaging teeth 22 and 23.

A plurality of transversely disposed apertures or slots 32 are formed in the bottom 15 edge 33 of the housing 10, and their adjacent sides turned down or rounded, as at 34, to eliminate sharp edges or corners. A plurality of small key retaining rings 35 are adapted to extend into slots 32 and are normally retained therein, by a flexible member 36 passing therethrough, as shown in Figs. 5 and 6. This member may be either a cord or small chain or any other material which will be sufficiently flexible to accomplish my purpose as hereinafter explained.

The cord 36 is passed around the reel 14, and secured thereto at one end; and from the reel it is passed over a guide member 37 and its opposite end secured to the case 10, 30 as at 38, so it will normally overlie the slots 32, as shown. The guide 37 may be either an arcuate piece of metal, fixed to the housing 10, or may be in the form of a small pulley, as shown in Fig. 7. Rings 35 will be 35 split so that keys 39 may be removably secured thereto.

While any suitable construction and arrangement of the reel 14 and actuating means, including the means for holding it against 40 rotation by the spring 20 and the means for disengaging this holding means, to permit rotation by the action of spring 20, may be used, that here shown and described will serve my purpose and will be preferred.

Also any type of key retaining means may 45 be used in place of the rings 32, so long as they are arranged to slide free, upon the end 36. Various kinds of snap fasteners may be used for this purpose.

For encasing keys 39, a suitable flexible cover 40 may be secured over the housing 10, as shown in Figs. 1 and 2; the free ends 42 thereof being provided with a snap fastening means 43 for separably securing them together. This cover may be of leather or any other suitable pliant material. If desired it may be terminated a short distance beyond the edge 33 of the housing so the keys 39 will ordinarily extend beyond its end 50 edges, and the snap fastener 43 eliminated.

In use the keys 39 will ordinarily be enclosed within the case, as shown in Fig. 2. When it is desired to use a key the ends 42 are separated and thrown back as shown in 60 dotted lines. The proper key is then selected

and drawn out, as shown in dotted lines in Fig. 1, until it is entirely free of the case and may then be freely rotated, after insertion in a lock, without the necessity of likewise turning the case, as is common with the device of this character heretofore in use. When the key is pulled out the reel 14 is rotated against the action of spring 20, the teeth 23 riding over the teeth 22, against the action of leaf spring 25. When the selected 75 key is pulled out of the case to the desired extent the co-engagement of teeth 22 and 23 will hold the reel 14 against the action of spring 20. After being used the key is returned to its normal position between the 80 flaps 42 and adjacent the casing 14, merely by pressing on the button 27. This moves the reel 14 axially on the stud 15, against the action of spring 25, removing teeth 23 from engagement with the fixed teeth 22, 85 thereby permitting the spring 20 to rewind the cord 36.

In Fig. 7 I have illustrated a slightly modified form of construction. The principles here involved are identical with those above described and the structure is different only in making the housing 10^a circular and the flaps 42^a of like configuration.

While I have herein shown and described the preferred specific embodiment of my invention, in order that its principles of construction and operation may be readily understood, I nevertheless reserve the right to make such changes or modifications in the structure as will properly come within the 95 scope of the appended claims. As above stated, the mechanical details of structure and arrangement of the reel 14, together with its actuating and holding mechanism, may be altered without departing from the spirit of 100 my invention. Also, as the portions of the case edge 33 between the apertures 32 merely constitute guides and supports for the cord 36, these may be formed of a series of pins, or any suitable means provided, whereby 105 a plurality of keys may be carried on a single cord, in spaced relation, and individually drawn out for use without disturbing the others.

Having described a preferred form of my 115 invention, I claim:

1. In a device of the character described, the combination of a housing; a plurality of spaced apertures in one wall of the housing, arranged in alignment; a continuous flexible member in the housing adapted to overlie said apertures; means to hold the flexible member longitudinally movable over the apertures; key securing members extending into each of said apertures and carried longitudinally slidable on the flexible member, said members being of a size to prevent their passing through the apertures; and means in connection with the flexible member to normally hold the key securing mem- 120 125 130

bers adjacent the housing and to permit their being individually spaced therefrom without disturbing the others.

2. In a device of the character described, 5 the combination of a housing; a plurality of spaced apertures in one wall of the housing, arranged in alignment; a reel in the housing; a cord secured at one end to the reel and at its opposite end to the housing and 10 arranged to overlie the apertures; means to hold said cord longitudinally movable over the apertures; key holding members arranged longitudinally slidably on said cord and adapted to extend into each aperture, said members being of a size to prevent their passing through the apertures; spring means in connection with the reel to 15 normally hold said cord taut with the key holding members adjacent the housing and 20 being yieldable to permit any key held thereby to be moved away therefrom by drawing the cord through the adjacent aperture; means in connection with the reel to releasably hold it against the action of its spring 25 means and a flexible case in connection with

the housing to hold the keys normally flat relative thereto.

3. A key case comprising a housing; a plurality of spaced apertures in one wall of the housing, arranged in alignment; a reel in 30 the housing; a cord wound around said reel and secured thereto at one end, its opposite end being secured to the housing so that a portion thereof will extend past said apertures; means to hold said cord longitudinally movable over said apertures; key holding members extending into said apertures and loosely retained on said cord, said members being of a size to prevent their passing through the apertures; there being yielding 40 means in connection with said reel to normally hold said cord taut and the key holding members adjacent the housing and to permit longitudinal extensibility of the cord through said apertures. 45

In witness that I claim the foregoing I have hereunto subscribed my name this 31 day of March, 1925.

JOHN P. DE L'EAU.
